Specification forming part of Design No. 7,438, dated May 19, 1874; application filed May 8, 1874.
[Term of Patent 3½ years.]

CASE S.

To all whom it may concern:

Be it known that I, ALFRED HEALD, of Philadelphia, Pennsylvania, have invented a Design for a Carpet-Pattern, of which the following is a specification:

My design for a carpet-pattern is clearly illustrated by the figure in the accompanying drawing, and is of a foliated character throughout.

The principal members of the pattern are flowers *a b c* and a group of leaves and buds, *d*, surrounding which are stems and small

leaves *e*, gracefully arranged in scroll-like curves.

Irrespective of the colors employed, I claim—

The design for a carpet-pattern of the foliated character described, and represented in and by the accompanying drawing.

In testimony whereof I have signed my name to this specification in the presence of two subscribing witnesses.
